F. SCHAEFFER

Des. 121,932

CHENILLE ROBE

Filed June 1, 1940

FIG. 1.

FRANCES SCHAEFFER
INVENTOR

BY Crosby & Gauthier
ATTORNEY

UNITED STATES PATENT OFFICE

121,932

DESIGN FOR A CHENILLE ROBE

Frances Schaeffer, Los Angeles, Calif.

Application June 1, 1940, Serial No. 92,729

Term of patent 3½ years

To all whom it may concern:

Be it known that I, Frances Schaeffer, a citizen of the United States, residing at Los Angeles, in the county of Los Angeles, State of California, have invented a new, original, and ornamental Design for a Chenille Robe, of which the following is a specification, reference being had to the accompanying drawing, forming part thereof.

I claim:

The ornamental design for a chenille robe, as shown.

FRANCES SCHAEFFER.
